Primary Examiner — Janice Hallmark(74) *Attorney, Agent, or Firm* — Knobbe Martens Olson & Bear LLP(57) **CLAIM**

The ornamental design for an air moving device, as shown and described.

DESCRIPTION

FIG. 1 is a front perspective view of an air moving device showing the new design;

FIG. 2 is a rear perspective view thereof;

FIG. 3 is a front side view thereof;

FIG. 4 is a rear side view thereof;

FIG. 5 is a right side view thereof;

FIG. 6 is a left side view thereof;

FIG. 7 is a top view thereof; and,

FIG. 8 is a bottom view thereof.

The broken lines in the drawing views are included for the purpose of illustrating portions of the air moving device that form no part of the claimed design.

1 Claim, 8 Drawing Sheets# US D887,541 S
